SEALING APPARATUS FOR ELECTRON TUBES

Edwin Francis Nickl, West Caldwell, N. J., assignor to Radio Corporation of America, a corporation of Delaware

Application December 10, 1954, Serial No. 474,563

14 Claims. (Cl. 49—2)

This invention relates to electron tube sealing apparatus and particularly to an improved push-down device for use in such apparatus, for producing an improved seal and for desirably orienting electron tube work pieces to be joined in the seal.

One type of sealing apparatus in which the invention finds utility is employed to seal a flat glass stem of an electron tube mount assembly, across an open end of a tubular glass envelope. The mount assembly includes conducting leads extending from one face of the stem and an electrode assembly mounted on the other face of the stem and connected to the conducting leads through the stem.

In sealing the stem to the envelope aforementioned, it is the practice to manually insert the electrode assembly into the envelope through the open end thereof until the stem contacts the open end referred to. On completion of this manual operation, the resultant loose assembly, with the stem leads extending upwardly, is mounted on a sealing pin or support fixture of the sealing apparatus for transportation through a plurality of work stations at which sealing fires are directed to the region of juncture between the stem and envelope at which a seal is to be made.

As the glass at the region of juncture is softened by the sealing fires, it becomes displaced from this region. Due to a snug fit in which the electrode assembly aforementioned is received in the tubular envelope, the mount assembly is restrained against relative movement with respect to the envelope so that the glass disc of the mount assembly fails to follow to receding softened portion of the envelope.

This restraint of movement of the mount assembly, while involving the difficulty of aforementioned is desirable in making a seal with the work pieces inverted, since otherwise the weight of the mount assembly would produce an excessive force on the seal that might result in a fall of the mount assembly, including the stem disc thereof, into the tubular envelope. While "inverted" sealing is accompanied by the difficulty referred to, such sealing has important advantages such, for example, as permitting convenient support of the work pieces and displacing as far as possible the region to be sealed from the support fixture, to avoid excessive heating of the fixture.

Correction of this objectionable situation caused by the restraint against movement of the mount assembly is accompanied by difficulty because of variation in lead length from mount assembly to mount assembly. Therefore, a simple push-down of the mount assembly by engaging the free ends of the leads thereof has not proven satisfactory, since by this practice variations in lead length are reflected in the longitudinal dimensions of the sealed structures.

Accordingly, it is an object of the invention to provide an improved apparatus for sealing an electron tube mount assembly across the open end of a tubular envelope.

2

It is another object to provide an apparatus for desirably orienting a flat glass stem with respect to an open end of a tubular glass envelope and sealing the stem across the open end aforementioned to produce an improved seal and to assure uniformity in length of a plurality of structures formed by seals of the type referred to.

A further purpose is to provide a sealing apparatus adapted to engage the free ends of leads extending from one face of an electron tube stem and to move said stem a predetermined distance independently of the length of such leads, whereby a plurality of stems having leads of variable length are moved a uniform distance for improved seals and for uniformity in length of a plurality of structures sealed by the apparatus.

Another aim of the invention is to provide an improved push-down device for a sealing apparatus that is adapted to floatingly engage the free ends of stem leads of a loosely assembled mount and envelope structure, and to impart a thrust of predetermined magnitude to the leads only after such engagement has been effected, for establishing a desired engagement between the stem and envelope for an improved seal and for assuring uniformity in length of a plurality of structures so sealed.

25 A further object is to provide sealing apparatus including a push-down device having independent means for accomplishing a floating engagement with a work piece to be pushed down and for imparting a thrust to the work piece only after such engagement, causing a movement thereof of predetermined magnitude.

Further objects and features of the invention will become apparent as the present description proceeds.

Referring now to the appended drawing for a detailed consideration of an apparatus embodying the invention,

35 Figure 1 shows an elevation partly in section of a push-down device according to the invention;

Figure 2 is a top view of the device shown in Figure 1;

Figure 3 is a sectional view taken along the line 3—3 of Figure 1;

Figure 4 is a view in cross-section taken along the line 4—4 of Figure 3;

Figure 5 shows an elevation partly in section of a sealing apparatus according to the invention and with which the push-down device shown in Figure 1 is associated; and

Figure 6 is a view partly in section taken along the line 6—6 of Figure 5.

For convenience in describing an embodiment of the invention, there is shown in Figures 1 to 4 a push-down device according to the invention, and in Figures 5 and 6, there are shown a portion of a turret of a sealing apparatus with which the push-down device is adapted to be advantageously employed, as well as common actuating means for the push-down device and the sealing apparatus.

The turret

Referring first to Figure 5, a sealing apparatus embodying the invention includes a movable support comprising a turret 10, supported on a spindle, not shown, for intermittent rotation thereon. The periphery of the turret includes a plurality of sleeves 11, one of which is shown. Supported in sleeves 11 are a plurality of support fixtures 12, one of which is shown, rotatable on bearing 13.

Intermittent rotation of turret 10 is provided by a first power transfer means comprising a drum cam 14 having a track 15 defined by two raised surface portions 16, 17 as shown in Figure 6. The track 15 has an entrance portion 18 into which a roller pin 19 fixed to the underside of turret 10, is adapted to enter on rotation of drum 14 in the direction indicated by the arrow. The track 15 also

has an exit portion 20, from which another roller pin 21, also fixed to the underside of turret 10, is adapted to leave the track. The track is so shaped that during an appreciable portion of a cycle of rotation of drum 14, the pin 19 as well as turret 10 are held against movement by a portion of track 15 extending normally to the axis of drum 14. This portion may include an arc of 270°. The track has another portion that has a dimensional component extending axially of drum 14. This portion may extend through an arc of 90° to the exit end 20. When pin 19 is engaged by this last named portion of the track, the pin 19 is caused to follow the track and impart a rotating movement to turret 10. The drum 14 is fixedly mounted on a shaft 22, which is connected to a power source, not shown, for rotation at a constant rate.

The aforementioned rotating movement of turret 10 is of a magnitude to carry support fixture 12 from one sealing position to another. At one of such sealing positions, the support fixture 12 is disposed directly below lever member 23 which is a movable member of a push-down device to be described. In this position, work pieces comprising a tubular glass envelope 24 having an exhaust tubulation 25 received in the fixture 12, and a mount assembly including a glass disc 26 resting on the upper open end of envelope 24, leads 27 extending upwardly from the glass disc and electrode assembly 28 received in envelope 24, are adjacent burner 29, for heating a contacting region of the disc 26 and the envelope 24. On initially arriving at the position indicated, the position of the lever member 23 is as shown in Figure 1, with a flat underside thereof directly above the free ends of leads 27. For uniformly heating the region to be sealed, the support fixture 12 is provided with a pulley 30 engaged by a belt 31 which is connected to a power source, not shown, for rotating the support fixture and the work pieces thereon.

The support fixture 12 includes an inner sleeve 32 for supporting the work pieces aforementioned. This sleeve engages a track 33 for raising and lowering the work pieces in accordance with the requirements of some of the work stations of the apparatus.

The push-down device

Referring now to the push-down device according to the invention, it will be noted from Figure 1 that this includes an outer sleeve 34 fixed to a bracket 35. Bracket 35 is adjustably fixed to a rod 36 by means of a clamp 37. Rod 36 in turn is fixed to a clamp 38 by means of a screw 39. Adjacent the lower end of outer sleeve 34 is an inner collar 40 fixed to sleeve 34 by screw 41.

Within sleeve 34 is disposed an inner sleeve 42 for vertical movement therein. The inner sleeve is urged upwardly by an expansion spring 43 bearing on collar 40 and on a shoulder 44 formed on inner sleeve 42. The inner sleeve referred to is provided with a depression or keyway 45 extending longitudinally of the sleeve and serving to engage a key 46 fixedly wedged into an opening in bracket 35 for restraining rotation of sleeve 42 with respect to the outer sleeve 34 for a purpose to be described. The lever member 23 is pivotally supported on a tab 47 extending downwardly from the inner sleeve 42.

The lever member 23 comprises a structure including a shank 48 having a curved upper surface 49, an arm 50 extending laterally from shank 48, and a flat plate 51 fixed to arm 50. The lever member 23 is pivoted on a pin 52 on a horizontal axis. The pin referred to engages a lower portion of shank 48 and extends normal to the direction of curvature of shank surface 49. The plate 51 has an undersurface for engaging the free ends of leads 27 of a mount assembly work piece.

The inner sleeve 42 has an upper portion 53 as shown in Figure 4, of reduced wall thickness. This reduction in wall thickness provides a shoulder 54 having a function to be described. Embracing the portion 53 of the

inner sleeve, is a yoke 55 having an integral arm 56 and supporting two shoes 57, 58. Each shoe includes a cylindrical shank portion 59 and a rectangular head portion 60 of appreciably larger transverse extent than the shank portion. The cylindrical shanks of the shoes are snugly received in opposite openings 61, in yoke 55, one of which is shown in Figure 1. The shoes referred to are spaced from each other to permit the thinned down portion 53 of inner sleeve 42 to extend therebetween, as shown in Figures 3 and 4.

The yoke 55 is pivoted on a pin 62 supported in brackets 63, 64 fixed to bracket 35. The integral arm 56 of the yoke extends upwardly and is connected to a link 65 by means of a pin 66. The link 65 is connected through a sleeve 67 to a second power transfer means comprising a piston 68 extending into a pneumatic cylinder 69, as shown in Figure 1. The cylinder 69 is supported by a standard 70 fixed to bracket 35. From the foregoing, it will be seen that an extending movement of piston 68 will cause the yoke 55 to rotate on pin 62 in a counterclockwise direction. To limit the magnitude of such rotation an adjustable screw 71 is mounted adjacent the end of yoke 55 remote from arm 56 and abuts against a stop 72 at the end of a desired rotary movement of yoke 55.

The aforementioned spring 43 urging the inner sleeve 42 upward causes the shoulder 54 to engage the lower surfaces of the rectangular heads 60 of the shoes 57, 58. Therefore, when the yoke 55 is caused to rotate in a counterclockwise direction as aforementioned, the shoes referred to are caused to bear downwardly on the shoulder 54 thereby causing the inner sleeve to move downwardly through a distance determined by adjustable screw 71, for a purpose to be described.

A rod 73 is positioned within the inner sleeve for vertical movement therein. Relative rotation between the rod and sleeve referred to is restrained by a pin 74 extending through the rod 73 and through oppositely disposed slots 75, 76 in the inner sleeve 42. The slots referred to extend axially of the sleeve to permit relative vertical movement between the rod 73 and sleeve 42. The lower end of the rod 73 is provided with a surface 77 having a curvature similar to that of surface 49 of the shank 48 and extending in the same direction. Since the shank 48 is pivoted to tab 47 fixed to sleeve 42 and since relative rotation of sleeve 42 and rod 73 is restrained by pin 74, the unidirectional extent of the curvatures of surfaces 49 and 77 is preserved, for a purpose that will appear clearly in the following.

The rod 73 is fixed to a third power transfer means comprising a piston 78 by means of a sleeve 79 having a cross arm 80. The piston 78 extends into a pneumatic cylinder 81 supported on side plates 82, 83 fixed to bracket 35, as shown in Figures 1 and 2. Compression springs 84, 85 engaging opposite ends of cross-arm 80 and a bracket fixed to the upper end of cylinder 81, as viewed in Figure 1, serve to urge the rod 73 upwardly. It will be noted from the foregoing that an extending movement of the piston 78 from the cylinder 81, will cause the rod 73 to move downwardly.

The magnitude of such downward movement is determined by the distance separating the curved surfaces 49, 77 and the distance between a nut 86 threaded to the thinned down portion 53 of the inner sleeve 42, and the upper surfaces of shoes 57, 58 as shown in Figure 4. Thus, downward movement of rod 73 first causes its lower surface to engage the upper surface of shank 48 and lock the lever 23 against rotation. Since the shank is pivoted to tab 47 fixed to inner sleeve 42, further downward movement of the rod after such engagement exerts a downward force on sleeve 42 to cause the latter to move downwardly. The magnitude of downward movement of the sleeve 42, however, is effectively stopped when the nut 86 engages the shoes 57, 58 and the yoke is restrained

from rotation by engagement between screw 71 thereon and the stop 72. A lock nut 86a serves to lock the nut 86 in desired position.

The common actuating means

A common means is provided for controlling the intermittent movements of the turntable or turret 10 and the push-down device described herein. This means comprises the shaft 22 shown in Figure 5 to which are fixed the drum 14 for imparting intermittent movements to the turret, and a cam 87. It will be seen that the cam 87 is provided with upper and lower dwells, successively engaged by a lever 88 having at one end thereof a cam follower 89 and at the other end a turn down portion 90 engaging a pin 91 outwardly urged by means, not shown, and associated with an air valve 92 shown schematically. This air valve may be of a type available in the trade and therefore requires no further description herein. The lever 88 constituting an actuating means, is pivotally mounted intermediate its ends on a pin 93 fixed to a standard 94 mounted on the base 95 of the sealing apparatus.

It will be seen from the positions of the track 15 on drum 14 and the cam 87, as shown in Figures 5 and 6, that pin 19 of the turntable has just entered the portion of track 15 that extends normal to the axis of the drum, and that cam follower 89 is approaching the raised dwell on cam 87. Continued rotation of shaft 22 through an arc of 270° serves to hold the turntable 10 stationary, and to bring the raised dwell on cam 87 into engagement with cam follower 89. In approaching the raised dwell aforementioned, the lever 88 is rotated on pin 93 in a clockwise direction. Such rotation causes the downwardly extending portion 91 of the lever to apply a downward pressure to valve pin 91, which results in an opening of valve 92, to permit communication between a conduit 95 connected to a source of air under pressure, not shown, and a conduit 96 connected to pneumatic cylinder 69.

The consequent build-up in air pressure in cylinder 69 causes the piston 68 to move to an extended position. Such movement of the piston imparts rotation to pin 62 in a counterclockwise direction as viewed in Figure 1, through link 65 and arm 56. Fixed to pin 62 is a lever 97 having an adjustable screw 98 locked in position by a nut 99, and a rotatable with the pin 62. Rotation of the lever 97 in a counterclockwise direction causes an end of screw 98 to engage a lever 100 pivoted on a pin 101 and to swing the lever to the left as viewed in Figure 1. Such movement of the lever causes it to depress a pin 102 urged to outwardly extend, by means not shown, from an air valve 103, shown in Figure 2, for opening the valve 103 to provide communication between an air conduit 104 connected to air conduit 96, and air conduit 105, connected to the air cylinder 81. Air cylinder 81 is thus energized, causing extension therefrom of piston 78 for a push-down operation.

To facilitate a smooth performance of the aforementioned several operations of the pistons 68 and 78, fluid flow control valves 106 and 107, shown schematically in Figure 1, are disposed across conduits 96 and 105 respectively. These control valves are a form of needle valve that may be very accurately screw adjusted to provide any desired rate of fluid flow. Valves of this type are well known and are not believed to require further description herein.

Adjustments of the push-down device

Certain adjustments of the apparatus are required to accommodate it to the dimensions of the work pieces processed thereby. In the instant example, the work pieces comprise a tubular glass envelope and a mount assembly intended to constitute, when sealed together, a subminiature type of electron tube.

One of the adjustments is made to provide desired clearance between the plate 51 of the push-down device

and the leads 27 carried by support fixture 12, during movement of the support fixture to a position directly below the plate. Thus, the vertical position of bracket 35 on rod 36 is adjusted by means of clamp 37 to position the plate about one-eighth of an inch above the leads. This assures desired clearance even though the length of leads 27 vary within a tolerance of one-sixteenth of an inch from work piece to work piece.

To permit a desired magnitude of descent of the plate 51 to floatingly engage the leads 27, screw 71 is adjusted so as to be spaced slightly more than one quarter inch from the stop member 72, to allow the shoes 57 and 58 engaged by an intermediate portion of the yoke 55 to move downwardly about a quarter of an inch for lowering the lever 23 into a floating or forceless engagement with leads 27.

Adjustment is also necessary of the magnitude of the downward thrust of the push-down device after the aforementioned floating engagement has been effected and after the lever 23 is locked against rotation, as will appear more clearly from the following description of the operation of the apparatus. This adjustment is made by turning nut 86, as shown in Figure 4, on the thinned down portion of inner sleeve 42 to provide a desired spacing between the lower side of the nut and the upper sides of shoes 57, 58. This spacing, in the example under consideration, is about 50 mils.

It is also necessary that the positions to which the inner sleeve 42 and the rod 73 are urged by springs 43, 84 and 85, be such as to separate the curved surfaces 77, 49, to permit a floating engagement as aforementioned between the lever 23 and a work piece to be pushed down. It will be noted that a stop to upward movement of the sleeve 42 is provided by the piston 68 when fully retracted. A similar stop to upward movement of rod 73 is provided by piston 78. All that is needed therefore to assure a desired spacing between the curved surfaces 77, 49, is to fix the length of rod 73 to provide this spacing when both pistons 68 and 78 are fully retracted.

Operation

In considering in more detail the operation of the apparatus, movements of the apparatus subsequent to the position shown in Figure 1 will be dealt with. The positions of the plate 51 and the support fixture 12 as shown in Figure 1, are those assumed immediately after termination of an intermittent movement of turntable 10. At this portion of the cycle of operation, the cam follower 89 engages a riser portion of cam 87 and is moving upwardly thereon. The valve 92 has not yet been opened, so that the plate 51 and the leads 27 are still in the same vertical positions they assumed during the preceding intermittent movement of the turntable. In these positions, the lever 23 is inclined from the horizontal and the portion of plate 51 closest to the leads 27 is spaced about an eighth of an inch therefrom, in accordance with an adjustment previously referred to herein.

Continued rotation of shaft 22 preserves a fixed engagement between turntable pin 19 and the portion of track 15 that is normal to the axis of shaft 22 throughout an arc of rotation of shaft 22 of 270°, which serves to hold the turntable from rotation. Such continued rotation of shaft 22 through the aforementioned arc also causes the cam 87 to rotate to cause the cam follower 89 to move to the upper dwell of the cam which may extend through an arc of about 200°. Such movement of the cam follower rotates lever 88 causing its downwardly extending portion 90 to press down to open valve 92. When the valve 92 is opened piston 68 becomes extended, rotating the yoke 55 until the screw 71 abuts against the stop member 72. Such rotation transmits a downward force on the inner sleeve 42 through the shoes 57, 58 engaging a shoulder of this sleeve. This force results in a downward movement of the inner sleeve 42 and the lever member 23 mounted thereon. The magnitude of

this downward movement, by virtue of the adjustment aforementioned of screw 71, is about one quarter inch. This movement is sufficient to cause the underside of plate 51 to engage the free ends of leads 27 in spite of the aforementioned tolerable variation in lead length. During such engagement, the lever 23 is free from restraint by rod 73 and consequently is rotated clockwise to the position shown in Figure 5.

As the yoke 55 is rotated to impart downward movement to sleeve 42 and lever 23, the pin 62 and the lever 56 are also caused to rotate, bringing the screw 98 into engagement with lever 100 and moving this lever against valve pin 102. This opens valve 103 causing the piston 78 and the rod 73 fixed thereto to move downwardly. Due to the actions of flow control valves 105 and 107 the actuators of pistons 68 and 78 is restrained to provide relatively smooth movements thereof. This restraint assures a complete downward movement of sleeve 42 and lever member 23 to floatingly engage the leads 27 before the rod 73 is impelled downwardly. Downward movement of the rod causes its lower curved surface 77 to engage the upper curved surface 49 of the shank 48 to first lock the lever 23 against rotation and then to move the assembly including the lever 23 and the inner sleeve 42 downwardly a distance of about 50 mils which is determined by the spacing between the nut 86 and the shoes 57, 58. This causes the leads 27 and the glass disc 26 through which they extend, to be moved downwardly about 50 mils. This magnitude of movement is permitted by a softened condition of the contacting portions of the disc and the envelope 24, produced by burner 29 at this station and similar burners at preceding work stations, and is necessary for a good seal.

During the foregoing push-down operation, the support fixture 12 is rotated by belt 31, to uniformly heat the periphery of the region to be sealed.

The foregoing operations of the apparatus take place during rotation of shaft 22 through the aforementioned arc of 270° and during which the turntable 10 is stationary. Further rotation of shaft 22, causes the pin 19 to enter the portion of track 15 that has a component extending axially of the shaft, and causes the cam follower 89 to engage a fall on cam 87. As a consequence, the outwardly urged valve pin 91 is free to move to extended position thereby closing valve 92. This deenergizes the cylinders 69 and 81 permitting the piston 68 to retract in response to the force of expansion spring 43, and the piston 78 to retract in response to the force of compression springs 84, 85. The aforementioned actions result in a raising of lever member 23 to its initial position to permit a succeeding support fixture and work pieces carried thereby to be brought to a position directly below the plate 51 of the lever.

The curvature in end surface 77 of rod 73 and the upper surface 49 of shank 48 are advantageous in that they permit a maximum area of contact between the rod 73 and lever 23 for locking the lever 23 against rotation immediately on engagement between the two surfaces mentioned. The curvatures are also advantageous in that they permit the aforementioned engagement to take place as a consequence of the same downward displacement of rod 73, in spite of variations in angular position of the lever 23. The curved surfaces referred to are kept in desired orientation angularly by means of pin 74 to permit the aforementioned contact therebetween.

It will be seen from the foregoing that an advantageous sealing apparatus is provided that contributes to the formation of an improved seal. While the push-down device described is particularly desirable in a sealing apparatus, it will be appreciated that it may find utility independently of such apparatus.

What is claimed is:

1. A sealing apparatus comprising a movable member, a movable support, a first power transfer means connected to said movable support for intermittently moving said

support in a path below and crossing the vertical axis of said member, a second power transfer means connected to said member for yieldingly lowering said member toward said support, a third power transfer means movable to engage said member for first locking said member against yielding movement and then pushing said member downwardly a predetermined distance while locked against yielding movement, and an actuating means connected to said second and third power transfer means, said first power transfer means having a structure for holding said support stationary during an interval between two intermittent movements thereof and directly below said member, said actuating means being connected to said first power transfer means for actuating said second and third power transfer means only during said interval, said support being adapted to support softened work pieces in a vertical array, whereby said member is adapted to engage the upper of said work pieces and to push it downwardly through said predetermined distance for an improved seal.

2. A sealing apparatus comprising movable means adapted to support glass work pieces to be sealed, a first power transfer means connected to said movable means for intermittently moving said movable means in a predetermined path, whereby said movable means and said work pieces are momentarily stationary at a predetermined position in said path, means adjacent said position adapted to heat said work pieces to soften a portion thereof, a movable member adjacent said position, a second power transfer means connected to said member for moving said member into a yielding engagement with one of said work pieces, a third power transfer means movable to first engage said member to convert said yielding engagement to a non-yielding engagement and then to move said member forcefully against said one of said work pieces, an actuating means connected to said second and third power transfer means, and a shaft connecting said first power transfer means to said actuating means, for actuating said second power transfer means only when said movable means is stationary.

3. A sealing apparatus comprising a first member movable only in a vertical path, a second member movably mounted on a lower portion of said first member, a support adapted to support two work pieces in a vertical array, a first power transfer means connected to said support for moving said support to a position directly below said second member, a second power transfer means connected to said first movable member for lowering said first and second members, whereby said second member is adapted to engage and respond in movement to the topmost of said work pieces, a third member movable in said path, a third power transfer means connected to said third member for moving said third member downwardly in said path for first engaging and locking said second member against movement in relation to said first member and then for lowering said first and second members a predetermined distance, whereby said work pieces are urged together for a good seal, actuating means connected to said second and third power transfer means, and a shaft fixed to said first power transfer means and to said actuating means for actuating said second and third power transfer means and deactuating said first power transfer means when said support is in said position.

4. A sealing apparatus comprising a movable support fixture, means for moving said support fixture intermittently in a predetermined path, whereby said fixture is successively stationary momentarily in a plurality of spaced positions in said path; means adjacent one of said positions adapted to heat to sealing softness work pieces supported in superposed relation on said support; a push-down device adjacent said one of said positions, said push-down device including a member adapted to engage the topmost of said work pieces, a vertically movable support for said member, said member being pivoted

to said support adjacent the lower end thereof for pivotal movement on a horizontal axis, means including a lever movable for lowering said support a predetermined distance to cause said member to engage the topmost of said work pieces and to be rotated thereby on said axis through a relatively small arc, and means for simultaneously locking said member against rotation on said axis and lowering said support another predetermined distance to cause said member to push down said topmost of said work pieces; said another predetermined distance for a good seal between said work pieces, said last named means including an actuating member in the path of movement of said lever; said means for lowering being actuated only when said support fixture is stationary in said one of said positions.

5. A sealing apparatus comprising in combination: a support fixture adapted to support two glass work pieces in superposed relation; a first power transfer means connected to said fixture for moving said fixture intermittently in a predetermined path, whereby said fixture is stationary in spaced portions of said path; means adjacent one of said portions for heating a contacting region of said work pieces to softness for sealing; a push-down device supported above said one of said portions and having a member movable pivotally on a horizontal axis and in a straight path vertically; a second power transfer means connected to said member and first moving said member downwardly a predetermined distance to contact and be pivoted by the uppermost of said work pieces, and a third power transfer means for simultaneously locking said member against pivotal movement and moving the locked member downwardly another predetermined distance for pressing said work pieces together; said first power transfer means holding said fixture stationary in said one of said positions during actuation of said second and third power transfer means.

6. A sealing apparatus comprising in combination: a movable support fixture adapted to support two softened glass work pieces in superposed relation; a push-down device including a vertically movable hollow support and a member movably mounted on said support for vertical deflection; a first means including a shaft connected to said fixture for moving the same; a second means connected to said vertically movable support for moving the same downwardly a predetermined distance to cause said member to engage the topmost of said work pieces; a third means movable vertically in said hollow support for engaging said member and simultaneously restraining said member from deflection and moving said support and member downwardly another predetermined distance, whereby said softened glass work pieces are pushed together for a good seal therebetween; and an actuating means connected to said shaft and to said second means for deactivating said first means during actuation of said second means.

7. In a sealing apparatus, a support fixture adapted to support two glass work pieces, means adjacent said fixture for heating contacting portions of said work pieces to plastic state, and a device adjacent said fixture and adapted to push said work pieces together to form a good seal therebetween, said device including a support mounted for movement toward said fixture, a member mounted pivotally on said support for pivotal deflection when said support is moved in one direction toward said fixture, means for moving said support a predetermined distance in said direction, and means for simultaneously restraining pivotal deflection of said member and moving said support further in said direction through another predetermined distance, whereby said member is adjustable to accommodate work pieces of different dimensions.

8. In combination, movable means adapted to support two glass work pieces in contacting relation; a first means including a shaft for intermittently moving said movable means in a predetermined path; means adjacent a portion of said path for heating the contacting re-

gion of said work pieces to a plastic state for sealing, a pressure device adjacent said portion of said path, said device having a floatingly mounted work engaging member, a second means movable in a predetermined path for moving said member toward said portion of said path for yieldingly engaging one of said work pieces on said support when said support is moved to said portion of the path, and a third means having a movable member extending in said path responsive to movement of said second means for simultaneously restraining floating movements of said member and moving said member against said one of said work pieces for compressing said contacting region; and an actuating means connected to said shaft and said second means for actuating said second means only between intermittent movements of said movable means.

9. A pushing device adapted to push a predetermined distance in one direction a work piece having a random dimension in said direction, said device comprising a sleeve mounted for movement in said direction, a work engaging member mounted adjacent one end of said sleeve for pivotal movement on an axis normal to said direction, means for moving said sleeve in said direction to cause said member to engage said work piece and to be pivotally deflected thereby, said means including a member movable in a predetermined path, and means including a movable member in said path and responsive to said means for moving for restraining pivotal movement of said member and for moving said sleeve and member while so restrained said predetermined distance in said direction.

10. A pushing device comprising a longitudinally movable elongated sleeve, a work engaging member mounted at an end portion of said sleeve for pivotal movement on an axis normal to said sleeve, a rod longitudinally movable in said sleeve, said rod having a cylindrically curved concave end surface, said member having a cylindrically curved surface, the radii of curvature of said surfaces being substantially the same, means for moving said sleeve longitudinally in one direction with said end portion leading, for causing said member to yieldingly engage a work piece having a random dimension in said direction, means for moving said rod longitudinally in said direction for causing said end surface of said rod to engage said curved surface of said member, and means engaging said rod and sleeve to restrain relative axial rotation thereof, whereby said surfaces provide contacting regions of relatively large area for effectively restraining pivotal movement of said member during a subsequent thrust by said rod on said member.

11. A contact responsive thrust device comprising a support movable in a rectilinear path, a feeler member mounted on said support for pivotal movement on an axis normal to said path, a combined locking and thrust member movable in said path for first locking said feeler member against said pivotal movement and then for moving said feeler member in said path, movable means connected to said support for moving said support and said feeler member a predetermined distance in one direction in said path, whereby said feeler member is adapted to engage a surface to which a thrust is to be given and to be pivoted on said axis by engagement with said surface, and means extending into the path of movement of said movable means for actuation thereby and connected to said thrust member for first moving said thrust member to engage said feeler member and to first restrain further pivotal movement of said feeler member and then to move said thrust member another predetermined distance in said one direction, whereby said feeler member is moved said another predetermined distance after engaging said surface for moving said surface said another predetermined distance.

12. A contact responsive thrust device according to claim 11, and wherein said feeler member has an arcuately curved surface, the center of curvature of said surface

comprising said axis, and said thrust member has an arcuately curved surface, said last named surface having a curvature similar to the curvature of said first named surface, said arcuately curved surface of said feeler member having a larger dimension in the direction of curvature than said arcuately curved surface of said thrust member, whereby said arcuately curved surface of said thrust member is substantially entirely engaged by a portion of the curved surface of said feeler member for effectively restraining said feeler member from pivotal movement during the movement of said thrust member through said another predetermined distance.

13. A contact responsive device according to claim 11, and wherein said feeler member has a first surface having an arcuate curvature determined by a radius extending from said first surface to said axis, and said thrust member has a second surface curved similarly to and in the same direction as said first surface, said surfaces being of unequal length in the direction of curvature thereof, whereby said thrust member engages said feeler member in a relatively large area of contact when said thrust member is moved to engage said feeler member.

14. A sealing apparatus comprising a movable support fixture adapted to support a work piece to be sealed, a first means connected to said fixture for moving the same to a predetermined position, a thrust device adjacent said position, said device including a sleeve movable in a path extending toward said fixture in said position, a feeler lever mounted on said sleeve at an end thereof adjacent said position for pivotal movement on an axis normal to said path, a thrust rod movable longitudinally in said sleeve, said feeler lever having a shank extending into

said sleeve, said shank having an arcuately curved free end surface, said axis constituting the center of curvature of said surface, said thrust rod having a free end surface adjacent said shank surface, and curved similarly to said shank surface and in the same direction, a second means having a movable member for moving said sleeve and said feeler lever a predetermined distance toward said fixture in said position, whereby said feeler lever is adapted to engage said work piece and to be pivoted on said axis, and a third means extending into the path of movement of said movable member and responsive to said movable member for first causing said free end surface thereof to engage said shank surface for restraining pivotal movement of said feeler lever and then causing said rod to move another predetermined distance toward said fixture, whereby said feeler lever is adapted to apply a thrust to said work piece through said another predetermined distance, said shank surface being longer in the direction of curvature thereof than said thrust rod surface, whereby said surfaces have relatively large areas thereof in contact in any one of a plurality of different positions to which said feeler lever is pivoted for effective restraint of pivotal movement of said lever.
